UNITED STATES PATENT OFFICE.

CORNELIUS K. CHAPIN, OF LANSING, MICHIGAN.

WIRE-FENCE MACHINE.

No. 888,784.

Specification of Letters Patent.

Patented May 26, 1908.

Application filed March 21, 1907. Serial No. 363,602.

To all whom it may concern:

Be it known that I, CORNELIUS K. CHAPIN, a citizen of the United States, residing at Lansing, in the county of Ingham and State 5 of Michigan, have invented a new and useful Wire-Fence Machine, of which the following is a specification.

This invention relates to machines employed in the manufacture of wire fences.

10 The machine forming the subject of the present invention is designed to manufacture fences of that type in which the longitudinal strands or warps are each formed of a pair of wires, and the transverse or picket 15 members are arranged at regular intervals, and are confined in place by the twisting of the wires between them, each pair of wires being twisted continuously in one direction until the insertion of a picket, and then twisted 20 continuously in the opposite direction until the insertion of another picket, after which the twist is made in the first direction.

One of the principal objects of the invention is to provide a machine in which the 25 twist may be made tighter at points immediately adjacent the opposite sides of the picket members, in order to firmly lock the pickets in place, while the intermediate portion of the cables may be twisted more 30 loosely, if necessary.

A further object of the invention is to provide a machine of the most simple construction by which the twisting operations may be carried on with uniformity, and stopped 35 in such manner as to form sheds for the introduction of the pickets at regular intervals.

A still further object of the invention is to provide a fence machine having a variable take up for the finished fabric, the take up 40 being arranged to operate at different speeds during the twisting operation.

A still further object of the invention is to provide a take up or feed that is started into operation after the beginning of the twisting 45 operation, and ceases to operate before the completion of each twisting operation.

With these and other objects in view, as will more fully hereinafter appear, the invention consists in certain novel features of construction and arrangement of parts, herein- 50 after fully described, illustrated in the accompanying drawings, and particularly pointed out in the appended claims, it being understood that various changes in the form, 55 proportions, size and minor details of the structure may be made without departing

from the spirit or sacrificing any of the advantages of the invention.

In the accompanying drawings:—Figure 1 is a side elevation of a wire fence machine 60 constructed in accordance with the invention. Fig. 2 is a plan view of the same. Fig. 3 is a transverse sectional view of a portion of the machine on the line 3—3 of Fig. 2, showing the arrangement of the twisters 65 and the beating up fingers. Fig. 4 is a sectional view of the same on the line 4—4 of Fig. 3. Fig. 5 is a detail perspective view of a portion of the transverse bar which supports the twisters and on which the picket 70 wire is supported prior to the beating-up operation. Fig. 6 is a plan view of the twister head at the right hand side of the machine. Fig. 7 is a similar view of one of the intermediate twister heads. Fig. 8 is a 75 similar view of one of the twister heads at the left hand side of the machine. Fig. 9 is an elevation of a portion of the mechanism shown in Fig. 1, illustrating on an enlarged scale the means for driving the feed or take-up roller. Fig. 10 is a plan view of the same, partly in section, on the line 10—10 of Fig. 9. Fig. 11 is a detail perspective view of the cam ring for controlling the intermittent movement of the feed or take-up roller. Fig. 12 80 is a detail perspective view of one of the feeding fingers of the drum detached. Fig. 13 is a sectional elevation of the winding roller on which the finished fabric is wound. Fig. 14 is an end elevation showing the detachable 85 friction bearing for one end of the roller. Fig. 15 is a detail perspective view of the actuating shaft and arm of the winding roller. Fig. 16 is a similar view of one of the disks or plates at the end of the winding roller. 90 Figs. 17 and 18 illustrate a modified construction of the feeding mechanism. Fig. 19 is a detail view on an enlarged scale of a portion of the fence.

Similar numerals of reference are employed to indicate corresponding parts throughout the several figures of the drawings.

The working parts of the machine are supported on a suitable framework 10, having 100 bearings for the support of a main shaft 11, the shaft 12 of the feed or take up, and the shaft 13 of the drum or roller on which the finished fabric is wound.

At one end of the machine is arranged a 110 transversely disposed bar 15 having a vertical web 16, and a horizontal web 17, the

vertical web being provided with openings 18 that are disposed in alinement with, and are arranged for the passage of twister heads 19, the number of twister heads employed being 5 dependent on the character of the fence manufactured, nine of such twister heads being shown in the present instance. Each twister head is in the form of a disk 20 having a pair of diametrically opposed openings 21 for the passage of the longitudinal wires x , of which each cable is formed. The disk is carried by a reduced neck 22 which projects from the forward end of a short shaft 24 mounted in a bearing in a standard 25, the 10 base of which is bolted to the web 17. Two of these shafts 24 are provided with small pinions 26, the teeth of which intermesh with the teeth of a gear wheel 27 that is mounted on a counter-shaft 28 supported in 15 suitable bearings 29, and the shaft of these twisters receive motion in the same direction at the same speed.

The shafts of the second, third, fourth, fifth, sixth, and seventh, twisters are provided with sprocket wheels 30 which are connected by a link belt 31, said belt being held in engagement with the sprocket wheels of idler rolls 32 that are journaled on stud bolts 33 carried by the vertical web 16 at points 20 between the several twister heads. The shafts of the seventh, eighth, and ninth, twister heads are provided with gears 34 that intermesh in a continuous train, these twisters being arranged so closely together 25 that better results are obtained from direct gear transmission, than by the employment of the sprocket wheels and belt.

All of the sprocket wheels, gear wheels, and the shafts which carry them are provided with passages 35 for the wires x , the wires being supplied from suitable reels, not shown.

Projecting from the forward face of the vertical web 16 is a series of projections 36 arranged in the same horizontal plane, and spaced apart at the twister heads, these projections forming a practically continuous support on which the picket is placed, and on which it rests before the beating up 50 operation.

At a point below, and in advance of the bar 15, is arranged a transversely disposed shaft 37, supported in hangers 38, and carrying at intervals a number of beating up fingers 39, there being preferably a pair of fingers for each of the cables or longitudinal strands of the fence, and one finger of each pair being disposed on each side of the cable. At one side of the machine is a lever 40 that is secured to the shaft 37, and is arranged within 55 convenient reach of the operator, and by moving the lever toward the right of Fig. 1, may force the picket from the supporting lugs 36 into the apex of the shed and hold the 60 same tightly in place until the twisting 65

operation behind the newly introduced picket has commenced, after which the fingers may be allowed to return to normal position in readiness to act upon a second picket.

On the shaft 11, previously referred to, is 70 mounted a pair of loose pulleys 43 and 44, that are driven, respectively, by belts 45 and 46, the belt 45 turning the pulley 43 in one direction, while the belt 46 turns the pulley 44 in the opposite direction. Keyed to the 75 shaft is a pair of clutches 47 and 48, said clutches being united by a centrally disposed sleeve 50 having an annular groove for the reception of the lower end of an operating lever 51 that is fulcrumed on a pin 52, and is 80 provided with an operating handle 53 by which the pair of clutches may be moved in either direction, movement in one direction locking the pulley 43 to the shaft, and movement in the opposite direction releasing the 85 pulley 43 and locking the pulley 44 to said shaft, so that the shaft may be rotated alternately in opposite directions.

The shaft 11 carries a pinion 55 that is in 90 constant mesh with the gear 27, and in operation will rotate the latter first in one direction, and then in the opposite direction, so that all of the twisters will receive a corresponding movement, it being designed to 95 twist the wires alternately in opposite directions between successive pickets. The gear 27 receives one complete rotation at each operation, and the movement is timed and governed by a disk 56 that is secured to the 100 shaft 28, and is provided with a peripheral notch 57 that is arranged to receive a stop lug 58 carried by a slidtable bar 59. The bar is mounted near one end in a guide 60 carried by the frame, and at its opposite end is pivotally connected to the operating lever 51. 105

The bar is further guided by a hanger 62, and between the hanger and guide 60 the shaft is surrounded by two helical compression springs 63 and 64 that are separated from 110 each other by a collar 65 rigidly secured to the shaft. When at rest, the springs tend to maintain the bar 59 in a central position with the lug 58 in the notch 57, and thus stop rotative movement of the disk 56, and the twister heads, and at the same time move 115 the operating lever 51 to a vertical position where both clutches are inoperative, and the pulleys 43 and 44 may be rotated idly. In the operation of this portion of the mechanism, the operator grasps the handle 53 and 120 moves the latter to the right, pulling the rod 59 against the stress of the spring 64, and moving the lug 58 from the notch 57. At the same time the clutch 47 is moved into engagement with the clutch face 43, and the 125 latter is locked to the shaft 11, whereupon movement is transferred to the shaft, and from thence through gear 55 to the gear 27 and all of the twister heads. The disk 56 rotates, and as soon as its movement com- 130

mences, the operator will release the handle 53, and spring 64 will thereupon press the side of the lug 58 against the vertical side of the disk 56, and the partswill continue in this 5 relation until disk 56 has made one complete revolution, this revolution being sufficient to revolve all of the twister heads and twist the cables between two pickets. When the notch 57 of the disk comes opposite the lug 58, the 10 latter is forced into the notch by spring 64, and the further movement of the disk is prevented. At the same time the clutch lever moves to the central position, and the pulley 43 is released, and allowed to rotate idly. A 15 fresh picket is then placed in position on the projections 36, and the operating lever 40 is moved to engage the fingers 59 with said picket, the latter being forced in the apex of the shed. The operator then pulls the handle 20 53 of the shaft and moves the lug 58 out of the notch against the stress of the spring 63. This movement forces the clutch 48 into engagement with the clutch face of the pulley 44, and the shaft 11 is again rotated, 25 but this time in the opposite direction, and movement is transferred, as before, to the twister heads, save that they turn in the opposite direction. As soon as the movement starts, the notch 57 passes beyond the lug 30 58, and the operator then releases the handle 53. As the disk 56 completes its rotation, the notch 57 again moves opposite the lug 58, and the latter is forced into the notch by the spring 63, thus again stopping the 35 rative movement, and again forcing the clutch operating lever to the vertical or central position, so that clutch 48 is moved from engagement with the pulley 44, and the latter rotates idly.

40 The shaft 12, previously referred to, carries a take up or feed drum 70 which may be formed of any material. In the present instance a wooden drum is employed, and in the face of the drum are secured the base plates 45 71 of feeding fingers 72. These feeding fingers are arranged in pairs, the space between each pair being designed to receive one of the longitudinal cables of the fence, and there are as many pairs of fingers as there are 50 cables in the fence. The drum is shown as provided with four sets of fingers arranged at ninety degrees apart, each set extending completely across the drum in a direction parallel with the axis thereof. Secured to 55 the end of the drum is a disk 74, carrying a series of lugs 75, there being four of such lugs in the present instance, and said lugs being spaced at ninety-degrees from each other. Through these lugs the feed or take up drum 60 is intermittently rotated.

One end of the shaft 12 finds a bearing in a hollow shaft 76, that is in the form of a hub extending inward from the rear face of a bevel gear 77, and this hollow shaft or hub is 65 mounted in a suitable bearing 78 carried by

a bracket 79 that forms a part of, or is carried by the main frame.

To the side frame is bolted a bracket 80 having a bearing for one end of the main shaft 11, and being further provided with a bearing for the end of a shaft 81, the opposite end of which is mounted in a bearing in the bracket 79. This shaft 81 extends diametrically across the face of the bevel gear 77, and carries two bevel pinions 82 and 83, 75 both of which are mounted loosely on the shaft. The shaft 11 carries a pinion 84 that intermeshes with a gear 85 on the shaft 81, and rotates the latter first in one direction, and then in the opposite direction, the movement imparted to the bevel gear 77 being first to the extent of one hundred and eighty degrees in one direction, and then one hundred and eighty degrees in the same direction, as distinguished from the movement of 80 the shaft 11 which rotates first in one direction, and then in the opposite direction.

The hub of the bevel pinion 82 is keyed to a clutch member 87, having clutch teeth engaging similar teeth formed in a clutch member 88 that is keyed to the shaft, and is held against the clutch 87 by a spring 89. The bevel pinion 83 is similarly mounted, and is arranged to be operated by a clutch member 90 held in clutching position by a spring 91. 95 The ratchet teeth of the respective clutches, however, face in opposite directions, so that when the shaft 81 is rotated in one direction, one clutch only will be operated, and one of the gears will rotate, while the other gear remains idle and its clutch inoperative. When the shaft is rotated in the opposite direction, the first bevel gear and its clutch will remain inoperative, while the second bevel gear and its clutch are secured to the shaft and im- 100 part movement to the bevel gear 77.

To the inner end of the hollow shaft or hub 76 is rigidly secured an arm 93, that is provided at its outer end with a guiding box 94 for a stud 95, that is movable in the direction 110 of its length, its inner end having a flat face for engagement with the lugs 75 of the feed or take up drum. The opposite end of the stud has an enlarged head 96, between which and the base of the pocket is arranged a helical compression spring 97, tending normally to force the stud 95 out of engagement with the lug 75, and to force the head of the stud into engagement with a stationary cam ring 98. The cam ring 98 has a central hub that 115 is mounted on an extension of the bearing 78, and is revolubly adjustable thereon, a flange 99 projecting from the hub being provided with arcuate slots 100 for the passage of securing bolts 101, by means of which the cam 120 ring may be locked in adjusted position. The cam ring is provided with two shoulders 102 and 103, that are disposed at diametrically opposite points, and these shoulders are arranged substantially in alinement with two 125 130

of the studs 75 of the feed or take up drum, the depth of the shoulders being such that when the head 96 of the stud passes over said shoulders, the inner end of the stud will move out of engagement with the lug 75 with which it has previously been engaged.

In the operation of this mechanism, the parts are so timed that the arm 93 carrying the stud 95, will stop at a point mid way between two of the lugs 75. At the beginning of a twisting operation, movement is transmitted to the bevel gear 77 through the mechanism previously described, and the arm 93 is rotated to the extent of one-eighth of a revolution before it comes into engagement with one of the studs 75, and during this eighth of a revolution the twisting operation is being carried on without any forward pull or feed of the cables, so that the latter will be tightly twisted behind the picket, which has been entered in the shed. After completing one-eighth of a revolution, the stud 95 will engage one of the lugs 75 and will continue in engagement therewith until it has moved the stud 75 to an extent of ninety degrees, this distance being sufficient to take up a length of cable equal to the distance between two pickets, in the present instance twelve inches. The head 96 of the stud at this time moves over one of the shoulders 102 or 103 of the cam ring, and is moved outward by its spring 97 until the stud is free from the lug, thus stopping the feeding movement. The arm 93 continues to rotate to the extent of one-eighth of a revolution, again stopping at a point midway between two of the studs 75, and during this latter eighth part of a revolution, the twisting continues without any forward feed of the cables, so that the twisting in advance of a picket to be entered is tight, and is approximately the same as that at the beginning of the twisting operation, while between these two points, or during the interval of feeding the twisting is comparatively light. In this manner the twist is made very tight on both sides of each picket, and the latter will be firmly held in place, while at points between the pickets, the twist may be more open, so that there is no unnecessary strain on the wire, and a smaller quantity of wire may be employed in the manufacture of a fence of given length than where a tight twist is made throughout the whole length of the cables.

The winding drum 110 is mounted on a shaft 13, and said drum is held between two disks 111, both of which are bolted or otherwise secured to the drum. One end of the shaft passes through a bearing 113 having a cap member 114 that is hinged at one side to the lower bearing block, the opposite side of the cap carrying a notched lug 115 which receives the upper end of a bolt 116 that is pivoted on a pin 117 carried by the lower bearing block. The upper end of this bolt is thread-

ed for the reception of a nut 118 which may be tightened in order to hold the shaft 13 by friction in any position to which it is turned. The bearing is further of such nature that the cap member may be readily loosened and swung back to permit the removal of the shafts, the roll, and the completed fence wound thereon.

At that end of the winding drum opposite the bearing 113 is arranged a pair of bearings 120 for the reception of a short hollow shaft 121 on which is mounted a pulley 122 that is constantly driven by a belt from any suitable source of power, the pulley being so mounted as to slip on the shaft when sufficient frictional resistance is offered to rotation of said shaft. Extending through the hollow shaft 121 is a cylindrical pin 121' arranged in alignment with the shaft 13 and this pin extends into a central opening formed in the adjacent disk 111 in order to form a support for the end of the drum. The inner end of the hollow shaft 121 carries an arm 122' from which projects a lug 123 arranged to enter a notch 124 formed in the adjacent disk 111, the lug serving as a means for transmitting movement to the winding drum, so that the winding drum is held tight at all times, and always takes up any of the complete fencing which may pass the feed or take up roll. The slip of the pulley 122, however, is so regulated that it cannot pull the complete fencing over the feed roller, and turn said feed roller, the latter being held and constituting the sole means of insuring the proper step by step feed of the cables during the twisting operation. The winding drum, however, serves to take up the cable as fast as it is fed, and holds the winding drum from backward movement during the latter portion of the twisting operation, that is to say, after the stud 95 has moved from engagement with the winding drum lug 75.

With an apparatus constructed in accordance with this invention, a wire fence may be manufactured rapidly and economically, and the twisting operation is such that the picket members will be firmly secured in place without waste of wire.

In Figs. 17 and 18 is illustrated a modified construction of feeding mechanism. In this case the feed drum 70' has a smooth periphery and serves merely as a guiding roller. The shaft 12 carries a sprocket wheel 140 which is connected to a sprocket wheel 141 by a link belt 142. The sprocket wheel 141 is carried by a transversely disposed shaft 143 which receives intermittent rotative movement in the direction indicated by the arrow in Fig. 17. At the opposite ends of the shaft 143 are crank disks 144 having wrist pins 145 which are connected by links 146 to the opposite ends of a cross bar 147 that is supported on the side rails of the machine. To the lower face of the cross bar 147

are attached feeding fingers 148 that are arranged to engage with the transverse or weft wires at points on opposite sides of the longitudinal strands.

5 When the shaft 143 is rotated from the position shown in Fig. 17 and travels through an arc of 90 degrees, the twisters will be actuated, but the wires will not be fed. During this movement, the feeding fingers 148 will ride over the next adjacent picket or cross wire to the rear of the feed bar, and will be in position to engage said picket or cross wire during the time the shaft and crank disks make a further movement to the extent of one hundred and eighty degrees. During the final movement of ninety degrees, the wire is being twisted, so that during one half of the revolution of the crank disks the wires will be fed forward, and during the remaining half the feed bar will be retracted to engage another cross wire, the twisting operation being accomplished during the backward movement of the feed bar.

I claim:—

25 1. In a wire fence machine, means for twisting the wires of each longitudinal strand of the fence, and means for varying the degree of twist at points between adjacent pickets of a fence.

30 2. In a wire fence machine, means for twisting the wires which form each longitudinal strand of the fence, and means for controlling the degree of twist at different points in the length of the strand.

35 3. In a wire fence machine, an intermittently operable twisting mechanism for intertwisting the wires which form each longitudinal strand of the fence, and a variable feeding means operating during such twisting operation.

40 4. In a wire fence machine, twisters, means for operating the same, a feeding device for the wires being twisted, and means for starting the feeding device into operation after the twisters commence operation, and stopping such feeding device prior to the completion of each twisting operation.

45 5. In a machine for manufacturing wire fences, of that class in which spaced transverse pickets are united by strands formed of intertwined wires, means for twisting the strands, and means for controlling such twisting operation to form a tight twist immediately adjacent the pickets, and a relatively loose twist between such tight twists.

50 6. In a machine for the manufacture of wire fences of that class including transverse pickets united by longitudinal strands each formed of intertwined wires, means for twisting the strands, and means for controlling the degree of twist to form a tight twist on both sides of each picket, and a relatively loose twist between such tight twists.

65 7. In a wire fence machine, twisting devices for the longitudinal strands, a feed or

take up for the completed fence, and a feed or take up actuating device operating intermittently to effect a complete feeding movement in advance of the completion of each twisting operation.

70 8. In a wire fence machine, wire twisting devices, a feed or take up for the fence, and an operating means for commencing the movement of the twister, and then starting and completing movement of the feed or take up in advance of the completion of the twisting.

75 9. In a wire fence machine, an intermittently operable twister arranged to twist a given length of wire at each operation, and a feeding or take up device arranged to feed said given length of wire during a period that commences after the beginning of the twisting operation and ends before the completion of the twisting operation.

80 10. In a wire fence machine, an intermittently operable feed roller, and a feed roller actuating means arranged to move idly before imparting movement to the roller, and after the movement of said roller is completed.

85 11. In a wire fence machine, a feed roller having spaced teeth for engagement with the completed fence, spaced lugs connected to the roller, a revoluble arm, a stud carried thereby and arranged to engage the successive lugs, and means for controlling the engagement and disengagement of the stud and lug.

90 12. In a wire fence machine, a feeding roller having teeth for engaging the completed fence, spaced lugs connected to said roller, an intermittently revoluble arm, a spring pressed stud carried thereby and arranged to engage the successive lugs, a cam with which said stud engages, the cam controlling the engagement and disengagement of the stud with the lug.

95 13. In a wire fence machine, the combination with a feed roller, of a plurality of lugs connected thereto, a shaft, an arm carried thereby, a spring-pressed lug-engaging stud carried by the arm, a cam ring with which said stud engages, a gear secured to the shaft, and means for imparting intermittent rotative movement to said gear.

100 14. In a wire fence machine, a feed roller having a plurality of spaced lugs, a shaft, an arm carried thereby, a spring held stud carried by the arm and arranged to engage successive lugs, a cam ring with which the head of the stud engages, a bevel gear carried by the shaft, an operating shaft arranged to revolve first in one direction and then the opposite direction, a pair of loose pinions carried by the shaft and meshing with the bevel gear at diametrically opposite points, and automatic clutching devices for connecting one pinion to the shaft when the latter moves in one direction and for connecting the

second pinion to the shaft when it moves in the opposite direction.

15. In a wire fence machine, the combination with a plurality of twisters arranged to 5 revolve alternately in opposite directions, of a main shaft, means for driving said shaft first in one direction and then in the opposite direction, means for transmitting movement from said main shaft to the twisters, a feed 10 drum arranged for intermittent rotative movement in the same direction, and means for transmitting movement from said main shaft to said drum.

16. In a wire fence machine, the combination with a plurality of twister heads, of a 15 shaft, gearing connections between the shaft and twister heads, a notched disk carried by the shaft, a longitudinally movable spring pressed rod, a lug carried thereby and arranged to enter said notch, the rod being 20 movable to release the lug and the notch to permit rotation of the shaft, said lug being forced within the notch at the completion of each single rotative movement of the shaft 25 to stop the twisting operation.

17. In a wire fence machine, the combination with a plurality of twister heads, of a shaft receiving rotative movement first in

one direction and then in the opposite direction, means for connecting said shaft to the 30 twister heads, a notched disk carried by the shaft, a longitudinally movable rod having a lug entering said notch, springs tending to maintain said lug within the notch, said springs serving to restore the lug to position 35 in the notch when the disk has made one rotation in either direction.

18. The combination in a wire fence machine, of a main shaft, a pair of loose pulleys mounted thereon, twin clutches on the shaft 40 and arranged to lock said pulleys alternately to the shaft, a clutch operating lever, a plurality of twister heads, a counter-shaft, gearing connections between the main shaft, the counter-shaft and the twister heads, a notched 45 disk carried by the counter-shaft, and a spring held rod connected to the clutch operating lever and provided with a lug arranged to enter said notch.

In testimony that I claim the foregoing as 50 my own, I have hereto affixed my signature in the presence of two witnesses.

CORNELIUS K. CHAPIN.
